UNITED STATES PATENT OFFICE.

HENRY K. SPENCER, OF BOSTON, MASSACHUSETTS, ASSIGNOR TO THE BLANCHARD MACHINE COMPANY, OF CAMBRIDGE, MASSACHUSETTS, A CORPORATION OF MASSACHUSETTS.

MAGNETIC CHUCK.

1,125,198.

Specification of Letters Patent.

Patented Jan. 19, 1915.

Application filed January 31, 1913. Serial No. 745,402.

To all whom it may concern:

Be it known that I, HENRY K. SPENCER, a citizen of the United States, and a resident of Boston, county of Suffolk, and State of Massachusetts, (whose post-office address is 21 Nottingham street, Dorchester, Massachusetts,) have invented an Improvement in Magnetic Chucks, of which the following description, in connection with the accompanying drawings, is a specification, like characters on the drawings representing like parts.

This invention relates to magnetic holding devices, and more especially, though not exclusively, to magnetic chucks intended for holding small pieces of magnetic material, while such pieces are being worked upon.

My invention will be best understood by reference to the following specification, when taken in connection with the accompanying drawings, showing three illustrative embodiments, while its scope will be more particularly pointed out in the appended claims.

25 In the drawings: Figure 1 is a plan, partly in section, of one specific form of magnetic chuck embodying my invention; Fig. 2 is a sectional view of the chuck on line 2—2 of Fig. 1; Fig. 3 is a plan, partly 30 in section, of another form of magnetic chuck embodying my invention; Fig. 4 is a sectional view on line 4—4 of Fig. 3; Fig. 5 is a sectional view on line 5—5 of Fig. 3; and Fig. 6 is a sectional view of still another 35 form of magnetic chuck embodying my invention.

Referring first to Figs. 1 and 2 of the drawings, and to the embodiment of my invention which I have there shown for illustrative purposes, 7 is a work support formed of steel or other suitable magnetic material, and provided with a plurality of annular concentric chambers, herein four in number, designated by the numerals 8, 9, 10 and 11. 40 Located in these chambers, are suitable magnetizing coils 12, 13, 14 and 15, respectively.

It will be observed that the work support provides a continuous steel shell, without joints, above the coil chambers, and hence 45 the coils are protected from the entrance of water. This is a matter of great practical advantage where it is desirable to flood the pieces of work on the work support with water, while the work is being per-

formed, as, for example, on a grinding machine. The bottoms of the coil chambers are preferably closed by a plate 16, formed of magnetic material, as for example, steel, and secured to the work support by suitable means, herein several sets of screws 17, 18, 19, 20 and 21.

Currents of equal magnitude are passed through alternate coils in opposite directions, that is to say, currents pass through the coils 12 and 14 in one direction, and 65 through the coils 13 and 15 in the opposite direction, as indicated, for example, by arrows on the coils in Fig. 1. This creates concentric alternate poles of opposite polarity, thus causing a magnetic circuit to 70 flow around each coil, the direction of the lines of force being represented by dotted lines and arrows in Fig. 2. In order to provide for holding very small work pieces, I have made provision for sub-dividing each 75 pole piece, thus providing a plurality of pole pieces within the compass of a given cross-section of the coil.

In the present embodiment, instead of separating unlike poles by non-magnetic 80 separators adjacent the work face of the chuck, as heretofore, the work support extends from pole to pole, and the magnetic circuit is complete without the inclusion of the pieces of the work. The latter are 85 attracted and held by making suitable provision for diverting a part of the lines of force from their metallic circuit, and compelling them to flow through the pieces of work to be held. While this result may be 90 accomplished in other ways, it is herein produced by narrowing the path of the magnetic circuit adjacent the work surface of the chuck, as for example, by providing the work support with a series of closely-spaced 95 concentric grooves, which may be, and preferably are, filled with rings of suitable non-magnetic material as, for example, brass, these rings being designated by the numerals 22 to 33, inclusive. It will be understood that these rings may be altogether omitted, if desired, in which case, the 100 grooves will form air gaps performing the same function as the rings. The spacing between the bottoms of these rings, or 105 grooves, and the tops of the coil chambers is less than the spacing between each coil chamber and the adjacent coil chamber.

while the spacing between each ring, or groove, and the adjacent ring, or groove, is greater than the space between the bottoms of the rings and the tops of the chambers.

5 Hence, when pieces of magnetic work, as for example the work pieces 34, 35, 36, and 37, are laid upon the work support surface, since the effective cross section of the magnetic circuit between the bottoms of the

10 rings and the tops of the coil chambers is reduced, as described, the greater part of the magnetic flux will be compelled to flow between the rings and into and through the pieces of work, as represented by dotted lines in Fig. 2. It must now be evident that by utilizing the described construction, I am enabled to provide a magnetic holding device whose holding points are much more closely spaced than is possible in chucks of

15 20 the type in which there is an actual separation of the poles, this being so because of the practical minimum limit of size of the magnetizing coils.

25 magnetizing coils.
By the described construction, I am enabled to provide a chuck which will hold very thin pieces of work, as exemplified by the piece 34, and very small pieces of work, as exemplified by the pieces 35, 36 and 37, which could not be held, except at a limited number of points, on a chuck having more widely spaced holes. In the present type of chuck, therefore, the entire area is available for small pieces of work.

able for small pieces of work.

The chuck proper may be mounted in any suitable manner, but herein is secured to a driving gear 38, on which two metallic contact rings 39 and 40 are mounted, the latter being insulated from the gear by a ring 41 of insulating material. The contact rings 39 and 40, which in practice will be suitably connected to the magnetizing coils, cooperate with fixed brushes 42 and 43, which will be connected in circuit with a suitable source of current, not shown.

45 It will be understood that the features just described, relating to the mounting of the chuck, form no essential part of my present invention, and may be suitably varied as the circumstances require.

50 Referring now to Figs. 3, 4 and 5, wherein I have shown another form of chuck embodying my invention: In this form, the principle involved is the same as that in the form first described, but is applied to a rectangular chuck having a work support 44. This work support is provided with a chamber 45, and has a plurality of walls, herein four designated by the numerals 46, 47, 48, and 49, about which are placed suitable 55 magnetizing coils 50, 51, 52 and 53, respectively, within the coil chamber. The bottom of the coil chamber is preferably closed by a plate 54, of steel or other suitable magnetic material, secured to the work holder 60 by suitable means as, for example, a plu- 65

rality of screws 55, 56, 57, 58, 59 and 60. The sides of the chamber 45 may be closed by suitable plates 61—61. [—] will be supplied

by suitable plates 61—61. The magnetizing coils will be supplied with currents of equal magnitude, the direction of the current in each coil being opposite to that of the current in the next adjacent coil, as indicated, for example, by the arrows on the coils in Fig. 3. The passage of the current through the coils in this manner will set up in the magnetic mass 75 magnetic circuits flowing about the respective coils, as represented by dotted lines and arrows in Fig. 4. As a means for diverting a part of the lines of force from their natural magnetic circuit, and compelling such diverted lines to flow through the body held by the chuck, the magnetic work support 44 may be provided with a series of transverse grooves, which may be, and preferably are, filled with strips of non-magnetic material, such as brass, these strips being designated by the numerals 62 to 76, inclusive. It will be understood, however, that these strips may be altogether omitted if desired, in which case, the grooves will form air gaps performing the same function as the non-magnetic strips. In this form of my invention, as in the form first described, the grooves, or strips, are of such depth that 90 they reduce the effective cross-sectional area of the magnetic mass between the bottoms of the grooves and the tops of the chamber 45, the distance between these two points being less than the thickness of the walls 46, 47, 48 and 49. The space between each groove, or strip, and the next adjacent groove, or strip, however, is preferably greater than the distance between the bottoms of the grooves and the tops of the chamber, and hence the greater part of the magnetic flux will be compelled to pass between the grooves or strips, and into and through the pieces of work upon the work supporting surface. The construction and operation of this form of my invention, and the advantages secured thereby, are essentially the same as those of the form first described, the differences being chiefly in the shape of the chuck. Fig. 6, wherein I have

shape of the chuck.
Referring now to Fig. 6, wherein I have shown another form of magnetic chuck embodying my invention: In this form I have shown an attachment capable of being applied to a common form of magnetic chuck, 120 so as to secure the advantages of the forms already described.

In Fig. 6, the numeral 77 designates generally a magnetic chuck of common form, comprising a series of magnetic rings 78, 125 79, 80, 81 and 82, alternating with interposed non-magnetic rings 83, 84, 85 and 86, and forming annular chambers 87, 88, 89 and 90, in which magnetizing coils 91, 130 92, 93 and 94, are disposed. Preferably,

the bottoms of the chambers are closed by a magnetic plate 95, secured to the magnetic rings by several sets of screws 96, 97, 98, 99 and 100.

- 5 Currents of equal magnitude are passed through the magnetizing coils, the direction of the current in each coil being opposite to that of the current in the next adjacent coil, and operating in a familiar manner to set up 10 lines of force which will flow from one magnetic ring to the next, provided, however, that there is a magnetizable body placed upon the upper surface of the chuck. In this form of chuck, however, as has already 15 been stated, the space between the poles is necessarily so great as to preclude the holding of very small or thin pieces of work. Therefore, as a means for adapting this chuck to very small, or very thin, pieces of 20 work, I have provided an attachment in the form of a work-supporting plate 101, secured to the chuck 77 in any suitable manner, as by means of bolts 102 and screws 103. This work-supporting plate is provided with an 25 annular chambers 104, 105, 106 and 107, corresponding to, and disposed above, the non-magnetic rings 83, 84, 85, and 86, respectively, and these chambers are separated from one another by annular magnetic walls 30 108, 109 and 110, corresponding to, and disposed above the magnetic rings 79, 80, and 81, respectively. The chambers 104, 105, 106 and 107, may be, and preferably are, 35 filled with some suitable non-magnetic material, as, for example, Babbitt metal, in the form of rings 111, 112, 113 and 114. In this form of chuck, as in the forms already described, I provide suitable means for diverting a part of the lines of force from 40 their metallic magnetic circuit, and compelling such diverted lines to flow through the body held. In the present instance, this result is secured in a manner similar to that already described, the work-supporting plate 101 for that purpose being provided with a plurality of closely-spaced concentric grooves, which may be, and preferably are, filled with rings of suitable non-magnetic material, such for example as brass, 45 the rings being designated by the numerals 115 to 129, inclusive. It will be understood, however, that these rings may be altogether omitted, if desired, in which case, the 50 grooves will constitute air gaps performing the same function as in the forms already described, these non-magnetic rings reducing the effective cross-sectional area of the magnetic mass at a portion of its circuit, thereby compelling a portion of the lines 55 of force to pass into the body held, the principle and mode of operation being precisely the same as in the forms already described. While I have herein shown and described 60 three specific embodiments of my invention for illustrative purposes, and have disclosed

and discussed in detail the construction and arrangement incidental to three specific applications thereof, it is to be understood that the invention is limited neither to the mere details nor relative arrangements of parts nor to its specific embodiments herein shown, but that extensive deviations from the illustrated forms or embodiments of the invention may be made, without departing from the principles thereof as defined by 75 the appended claims.

Having thus described my invention, what I claim and desire by Letters Patent to procure is:

1. A magnetic holding device having, in 80 combination, means for producing lines of magnetic force, means forming an uninterrupted circuit of magnetic material, said means having provision for causing a part of the lines of force to pass from said magnetic material and compelling such lines to flow through the body held.

2. A magnetic holding device having, in 90 combination, a magnetizing coil, a work support consisting of a body of magnetic material forming a magnetic circuit within the support, and means to cause a portion of the magnetic flux to pass through a work piece on the support.

3. A magnetic holding device having, in 95 combination, a magnetizing coil, a body of magnetic material forming a magnetic circuit, and means to reduce the effective cross-sectional area of the magnetic mass at a portion of said circuit, thereby to compel a portion 100 of the lines of force to pass into the body held.

4. A magnetic holding device having, in 105 combination, a magnetizing coil, a body of magnetic material provided with a recess for said coil and providing a complete magnetic circuit about the latter, and a series of non-magnetic members extending part way only into the magnetic circuit thereby to divert some of the lines of force through the body 110 held.

5. A magnetic holding device having, in 115 combination, a magnetizing coil, an uninterrupted body of magnetic material adjacent said coil, and a plurality of non-magnetic members embedded in but extending part way only through said body.

6. A magnetic holding device having, in 120 combination, a magnetic mass provided with a recess, a magnetizing coil disposed in said recess, said mass forming a continuous path for a magnetic circuit, and means to narrow the path at a part of said circuit thereby to compel a part of the lines of force to pass outside of said path and through the work.

7. A magnetic holding device having, in 125 combination, a magnetic mass provided with a recess, a magnetizing coil disposed in said recess, and spaced non-magnetic means embedded in said magnetic mass, the spacing 130

between said non-magnetic means being greater than the space between said non-magnetic means and said recess.

8. A magnetic holding device having, in combination, a magnetic mass provided with a recess bounded on all sides but one with a magnetizable wall having a certain effective cross-section, a magnetizing coil disposed in said recess, and spaced non-magnetic means 5 embedded in said magnetic mass on the remaining side of said recess and reducing the effective cross-section of the remaining side to less than the effective cross-section of the said wall.

15. 9. A magnetic holding device having, in combination, a magnetizing coil or coils, and a magnetic body comprising a pole piece or pieces adjacent the coils, said magnetic body being provided with a plurality of grooves 20 so disposed between the poles as to facilitate the flow of the magnetic lines of force through the body to be held and cause the lines of force to enter and leave the body at a multiplicity of points.

25. 10. A magnetic holding device having, in combination, a magnetizing coil, and a body of magnetic material forming a magnetic circuit, said body having a work-supporting face provided with a plurality of recesses to 30 reduce the effective cross-sectional area of the magnetic mass at a portion of said magnetic circuit, thereby to compel a portion of the lines of force to pass into the body held.

11. A magnetic holding device having, in combination, a magnetizing coil, and a body of magnetic material provided with a recess 35 for said coil and providing a complete magnetic circuit of magnetic material about the latter, said body having a work-supporting face provided with a plurality of recesses 40 extending part way only into said magnetic material thereby to divert a part of the lines of force through the body held.

12. A magnetic holding device having, in combination, a magnetizing coil, and an un- 45 interrupted body of magnetic material adjacent said coil, said body being provided

with a plurality of recesses extending part way only through said body.

13. A magnetic holding device having, in combination, a magnetic mass provided with a recess and a magnetizing coil disposed in said recess, said mass forming a continuous path for the magnetic circuit, and having a 55 recess or recesses to narrow the path at a part of said circuit thereby to compel a part of the lines of force to pass outside said path and through the work.

14. A magnetic holding device having, in combination, a magnetic mass provided with a recess, and a magnetizing coil disposed in said recess, said mass being provided with a plurality of spaced recesses, the spaces between the last-mentioned recesses being 65 greater than the space between the last-mentioned recesses and the first-mentioned recess.

15. A magnetic holding device having, in combination, a magnetic mass provided with a recess bounded on all sides but one with a magnetizable wall having a certain effective cross-section, and a magnetizable coil disposed in said recess, said mass being provided on the remaining side of said recess 75 with a plurality of spaced depressions reducing the effective cross-section of the remaining side to less than the effective cross-section of the said wall.

16. A magnetic holding device comprising, in combination, a pole piece, a magnetizing coil or coils having cross-sections in which currents flow in opposite directions at opposite sides of said pole piece, and a work support comprising a series of separated 85 magnetic portions, there being a plurality of such magnetic portions within the width of each said cross-section.

In testimony whereof, I have signed my name to this specification, in the presence of 90 two subscribing witnesses.

HENRY K. SPENCER.
